DEVICE FOR ADJUSTING AND OPERATING
GUIDES IN THE PROCEDURE OF ROLLING
METALS

Per E. Svensson, Hagfors, Satra Strand, Sweden

Application December 2, 1949, Serial No. 130,634
In Sweden January 11, 1946

4 Claims. (Cl. 80—51)

1

The present invention relates to the art of metal rolling and more particularly relates to a rolling mill guide.

In the art of metal rolling for instance the production of round iron, the work-piece is to be directed into the round groove by means of guides. When the work-piece is inserted between the guides, the latter must be spaced sufficiently to allow for easy insertion of the work-piece between them. The guides must also be able to clamp the work-piece at the same instant as it is caught by the rolls and to guide the work-piece while it glides between them during the rolling. Normally this guiding is effected in such a manner that one guide is mounted in a guide box and the other guide is moved towards or away from the fixed guide by means of a screw or a wedge. Fine adjustment of the position of the work-piece in the axial direction of the rollers is then effected by the adjustment of screws upon which the fixed guide rests, or otherwise by means of plate spacers. For every work-piece that is rolled, the guides are worn and it therefore follows that subsequent work-pieces are moved more and more in the direction of the fixed guide, that is, the work-pieces are moved successively towards one side of the round groove as the rolling proceeds, whereby the rolled bar is not truly round. Coarse adjustment of the guides in the axial direction of the rollers is normally effected by displacement of the guide box proper. Thus, adjustment of the guides at the beginning of the rolling as well as adjustment of the same during the rolling is both time wasting and difficult.

The present invention therefore has for an object to provide a rolling mill guide particularly for use in the hot rolling of round bars incorporating in a guide box a laterally adjustable slide upon which is mounted a fixed guide and a movable guide.

It is a specific object of the invention to provide adjusting means for the guides, including a screw and means connecting the screw to the slide and the movable guide, whereby movement of the screw simultaneously moves the slide and fixed guide in one direction and the movable guide the same distance in the opposite direction.

It is a specific object to provide an arrangement in which a sleeve member is mounted concentrically of the screw for rotation therewith and means are provided coupling the sleeve to the slide so that rotation of the sleeve moves the slide and thereby the fixed guide in a direction opposite to the movement of the screw.

It is a still more specific object to provide in

2

the guide box adjusting means operable to adjust the lateral position of the slide and both guides simultaneously without disturbing the adjusted position of the guides relative to one another.

5 Further and more specific objects will be apparent from the following description taken in connection with the accompanying drawings, in which:

Fig. 1 shows a front view of a guide box for work-pieces, partly in section.

Fig. 2 is a side view of the same guide box.

Fig. 3 is a front view, partly in section, of a modified guide box; and

Fig. 4 is a side view of the guide box shown in Fig. 3.

In the drawings, the guide box includes a frame 1 screwed on to a bar in the stand. In the guide box is a slideway in which is mounted a guided slide 2, in which the guides 2a and 2b are inserted. One guide, 2a is adjustably fixed to the slide 2 by means of the screw 3 that projects through a slot in the upper wall of the guide box and the other guide 2b is inserted loosely in the slide 2. In the guide box there is mounted a second slide member 4, which is slidably guided in the guide box and may be moved laterally upon axial movement being imparted to screw bushing 5 and when the nut 6 is turned. The axial position of nut 6 is fixed by the washer 7 that is screwed to the end plate 8 of the guide box. The screw bushing 5 constitutes a part of the second slide member and is internally threaded and receives the externally threaded screw 9, which actuates the support member 10 that is guided in the slide 2. The screw 9 extends through a sleeve or socket 11, which is journalled in the second slide member 4 but cannot move axially thereof since the screw bushing 5 is screwed to the said slide member 4. At its inner end the socket 11 is externally threaded and in engagement with an internally threaded hole in the slide 2. Key grooves are respectively provided in the interior of socket 11 and exterior surface of the screw 9, and in said grooves are placed two wedges 12 which are held in their position by a washer and the coil spring 13. The pitch of the threads of the screw 9 and the socket 11 is the same. A turning of the screw 9 will cause this to bear upon the support member 10 to exert force upon the loose guide 2b and to move them laterally. The socket 11 is turned simultaneously, and hereby the slide 2 and the fixed guide 2a are moved the same distance in the opposite direction. Since the two guides move towards each other, no adjustment thereof is necessitated by the wear

they are suffering during the rolling. The wear of the guides is compensated for by an increased tightening of the screw 9. Every lateral adjustment of the guides at the beginning of the rolling is effected solely by turning the nut 6, the slide 2, in which both guides are inserted, being moved in one direction or the other. A possible adjustment at exchange of guides of different thicknesses is effected by removing the wedges 12 and turning the screw 9. The guide box has been tested for rolling of a plurality of profiles. An easy and quick adjustment as well as a more exact rolling have been observed in all cases. In certain cases the use of this box construction has made it possible to substitute expensive profile rollers for rolling profiles of similar shape but different width by one single profile groove for all dimension.

The constructions of the guide box according to Figs. 3 and 4 show a somewhat simplified embodiment of the guide box according to Figs. 1 and 2.

The guide box 1 is screwed to a bar in the stand. In the guide box is a guided slide 2, in which the guides 2a, 2b are mounted. One guide 2a is adjustably fastened to the slide 2 by means of the screw 3 and the other guide 2b is loosely mounted in the slide 2. In the guide box is also mounted a second slide member 4 guided for adjusting movement in a direction laterally of the axis of the guides upon turning of the screws 14 which respectively bear against opposite faces of the second slide member. In this form of the invention the screw 9 is screwed into the internally threaded aperture in the outer member of the two part slide member 4, said screw actuating the support member 10, which is guided in the slide 2. The screw 9 extends through the socket 11, which is turnable in but axially fixed relative to the slide member 4. The other end of the socket has an external thread which engages the internal threads in an aperture in the end wall of the slide 2. In the socket 11 and the screw 9 are respective key grooves, in which two wedges 12 are inserted. The pitch of the threads of the screw 9 and the socket 11 is the same, thus when the screw 9 is rotated it bears upon the support member 10 to exert force upon the loose guide 2b and move both support and loose guide in the lateral direction. The socket 11 is turned simultaneously, so that the slide 2 and the fixed guide 2a are moved the same distance in the opposite direction.

A lateral adjustment of the guides is effected by means of the adjusting screws 14. The movement of the second slide member 4 moving the slide 2, in which both guides are inserted, in one direction or the other depending on which adjusting screw is actuated.

It is therefore clear that the present invention provides a rolling mill guide in which the box structure 1 is provided with upper and lower parallel surfaces constituting respective slideways the axes of which extend transversely with respect to the direction of movement of the stock to be rolled. In both forms of the invention a slide member 2 including upper and lower parallel legs and a vertical connecting leg is displaceable along the slideway. A fixed guide member 2a is secured to the slide by a screw 3 extending outwardly of the box 1 through a slot in the upper leg thereof, and movably carried by the slide 2 is another guide member 2b. Between the movable guide member and the end connecting leg of the slide is a support member 10 with respect

to which the screw 9 cooperates to move the movable guide relative to the slide. In each arrangement illustrated an additional slide member is provided. This additional slide member is apertured and is composed of two elements. In Fig. 1 the slide 4 is cooperatively associated with the threaded bushing 5 to constitute a bearing for the socket or sleeve 11 and also to prevent axial movement of the socket when the screw 9 is rotated. In Fig. 1 this supplementary or additional slide member is confined between the upper and lower slideways of the box. In Fig. 3 the slide member projects through a slot in the top wall of the box and is acted upon by the screws 14 for adjusting movement of the main slide, the sleeve, and the guides carried by the main slide which move as a unit in either direction responsive to turning screws 14.

In the arrangement of Fig. 1 the bushing 5 is internally and externally threaded and the internally threaded nut 6 is mounted on the end plate of the guide box in such a manner that it cannot move axially relative to the end plate due to the positioning of the element 7 cooperating with the flange on the nut 6. It therefore follows that rotation of the nut 6 axially moves the bushing 5, the sleeve 11 and thereby the slide 2 carrying both the guide members.

It is therefore clear that the present invention provides an arrangement in which for wear take-up purposes a single adjustment comprising the rotation of the screw 9 in either arrangement provides simultaneous movements in opposite directions of the two guide members and for position adjustment prior to rolling rotation of the nut 6 in Fig. 1 displaces the unit comprising the slide and the two guide members, while in Fig. 3 this position adjustment is effected by the co-operation of the respective screws 14 with the supplementary slide 4.

Having now described my invention, what I claim as new and desire to secure by Letters Patent is:

- 45 1. A rolling mill guide including means defining a guide box through which stock to be rolled is guided, a first slide mounted within said box for movement with respect thereto in a direction transversely of the path of movement of the stock, a first guide member fixed to said slide for movement therewith, a second guide member carried by said slide for cooperation with said first guide member and movably mounted relative to said slide, a second slide member incorporated with said guide box and movable relative thereto, a sleeve rotatably journaled in said second slide member, means coupling said first slide member to said sleeve for movement axially thereof in a direction opposite to and simultaneously with axial movement of said second slide member when the latter is moved, said second slide member including an internally threaded bushing member concentric of said sleeve, a screw member having external threads thereon extending within said guide box in threaded engagement with said bushing for cooperation with said second guide member to move the same, means rotatably coupling said sleeve to said screw so that rotation and axial movement of said screw thereby imparts rotation and reverse axial movement to said first slide, said bushing being movable laterally of the guide box to impart movement to the second slide, an apertured end plate closing said guide box, an internally threaded nut rotatably mounted on said end plate,
- 50
- 55
- 60
- 65
- 70
- 75

means restraining said nut from axial movement, and said bushing member having external threads thereon engaging the threads on said nut whereby rotation of the nut axially moves said bushing member and thereby said second slide, said sleeve and said first slide.

2. A rolling mill guide including a guide box having upper and lower parallel frame members, said frame members each having a slideway thereon on the facing surfaces thereof, said slideways extending transversely of the path of movement of the stock to be rolled, a first slide within said box movable along said slideways and including upper and lower parallel legs and an apertured end leg, the aperture in the apertured member fixedly carried by said slide, a second guide member movably carried by said slide between said first guide member and said apertured end leg, a second slide member movably supported at least partially within said guide box and cooperating with at least one of the slideways for movement therealong, an externally threaded sleeve in threaded engagement with the aperture in the end leg of the first slide and journaled in said second slide member, said second slide member including apertured means preventing axial movement of said sleeve relative thereto and the aperture being concentric of the axis of said sleeve, and having threads thereon, a screw extending within said guide box in threaded engagement with the last mentioned threads embodied with said second slide member and extending through said sleeve for cooperation with said movable guide member to move the same when rotated, and means coupling said screw with said sleeve whereby rotation of said screw rotates said sleeve to thereby move said first slide member and the guide fixedly carried thereby in

a direction opposite to the direction of movement of said first guide member, and adjustable means restraining said second slide member from movement along said slideways.

3. A rolling mill guide as defined in and by claim 2, in which the upper frame member of said guide box is apertured and said second slide member projecting through said aperture, and said adjustable means comprising adjusting screws mounted for cooperation with opposite surfaces of said second slide member whereby movement of said adjusting screws imparts position adjusting movement to said second slide and said first slide and the guides supported thereby as a unit.
4. A rolling mill guide as defined in and by claim 2, in which the apertured means of said second slide member comprises an internally and externally threaded bushing, the said screw being in threaded engagement with the internal threads of said bushing, and said adjustable means comprising a nut rotatably supported in said guide box having internal threads engaging the external threads of said bushing, and means restraining said nut from axial movement whereby rotation of said nut axially displaces said bushing and thereby said second slide, said sleeve and said first slide as a unit.
